HYDRAULIC JACK

Ernest Strom, St. Paul, Minn.

Application December 16, 1944, Serial No. 568,438

7. Claims. (Cl. 60—52)

1

This invention relates to new and useful improvements in hydraulic jacks, and more particularly to such jacks adapted for use in the automobile industry, although it is to be understood they may be used for various other purposes, where applicable.

An object of the present invention is to provide a hydraulic jack which is extremely simple and inexpensive in construction and which embodies a minimum of working parts.

A further object of the invention is to provide a jack of the class described comprising a main cylinder having a ram mounted for reciprocal movement therein, and an operating handle mounted for pivotal movement with respect to said cylinder and having a fluid reservoir therein, and a pressure pump being carried by the handle and provided with a piston having an operative connection with a fixed portion of the jack, such as the main cylinder, whereby when the handle is oscillated relative to the cylinder the pump is operated to pump fluid from the reservoir into the cylinder, to raise or project the ram therefrom.

A further and more specific object is to provide a jack of the class described including an operating handle comprising a reservoir, a pressure pump, fluid circulating passages, and a fluid release valve, whereby all of said parts may be completely assembled in the handle as a unitary structure, and independently of the jack base and cylinder.

Other objects of the invention reside in the unique construction of the pump and the operating handle and in the arrangement of the fluid circulating passages through the pivotal connection between the operating handle and the jack cylinder; in the yoke provided for operatively connecting the pump piston to the jack cylinder whereby when the operating handle is oscillated the pump piston is operated to pump fluid from the reservoir into the main cylinder; in the provision of a simple and inexpensive release valve for releasing the pressure fluid from the main cylinder, and in the means provided at the outer end of the handle for conveniently operating the release to control the return flow of the fluid from the cylinder to the reservoir; in the provision of a jack of the class described comprising a pivoted operating handle which may readily be folded into a position substantially parallel to the main cylinder to facilitate storing the jack in a comparatively small space; in the simple construction and arrangement of the valve parts of the jack handle and fluid pump whereby

the entire apparatus may readily be manufactured in quantity production at extremely low cost; and in the provision of such a jack wherein all of the objectionable features now commonly inherent in conventional jacks of this general type have been substantially eliminated.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a vertical sectional view through the jack showing the general construction thereof;

Figure 2 is a detail sectional plan view on the line 2—2 of Figure 1, showing the pivotal connection between the operating handle and the main cylinders;

Figure 3 is an elevational view of a portion of the jack to illustrate the operating means for the pressure pump and

Figure 4 is a sectional plan view substantially on the line 4—4 of Figure 1.

The novel jack herein disclosed is shown comprising a suitable base 2 provided with a hub or boss 3 having a counterbore therein for receiving the lower end of a suitable cylinder 4. The lower end of the cylinder is suitably secured in the counterbore provided in the base plate 2 in leak-tight relation thereto, whereby the cylinder and base provide in effect, an integral structure.

The upper end portion 5 of the cylinder 4 is shown slightly enlarged to receive a suitable packing 6 retained in the enlarged end 5 by a packing nut or gland 7 which may, for convenience, be received in threaded engagement with the upper end portion 5 of the cylinder, as best illustrated in Figure 1.

A suitable plunger or ram 8 is mounted within the cylinder 4, and is shown having its periphery slightly spaced from the bore of the cylinder 4. The upper end of the ram 8 slidably passes through the packing 6 and the lower end of the ram is shown having a head 9 provided with a plurality of peripheral recesses or flutes 11, as indicated in Figures 1 and 2. The recesses 11 provide fluid circulating passages between the annular chamber or space 12 provided between the periphery of the ram 8 and the bore of the cyl-

inder 4. The ram 8 is shown having a reduced extension 14 whereby a space 13 is provided beneath the head 9 of the ram, as shown in Figure 1. The diameter of the extension 14 is relatively smaller than the diameter of the ram 8 whereby the pressure fluid entering beneath the ram head 9 may upwardly move the ram when the pressure pump, subsequently to be described, is operated.

A load-engaging member, generally designated by the numeral 15, has its upper end portion 16 adjustably secured to the upper end of the ram 8 by a suitable adjusting screw 17, received in threaded engagement with the ram 8 and having a swivel connection 18 with the offset end portion 19 of the load-engaging member 15. The adjusting screw 17 operatively connects the load-engaging member 15 to the ram 8 and provides means whereby the load-engaging member 15 may be relatively adjusted with respect to the upper end of the ram, thereby to extend the range of lift of the jack.

To further extend the usefulness of the jack, the load-engaging member 15 is shown provided with a lower load-engaging portion 21, which extends outwardly from the upright portion 21 of the member 15 and makes it possible to engage a load which may be disposed in close relation to the ground surface, as will readily be understood by reference to Figure 1. The lower end portion of the load-engaging member 15 extends inwardly, as shown at 22 in Figure 1, to engage the outer surface of the main cylinder, thereby to provide a support for the depending portion 21 of the load-engaging member 15 when said member is engaged with a load.

A suitable operating handle, generally designated by the numeral 23, is shown pivotally connected to the wall of the main cylinder 4 by suitable pivot studs 24 and 25. The stud 24 passes through an aperture 26 in a fork 27 of the operating handle 23 and is received in threaded engagement with a fitting or pivot element 28, suitably secured to the wall of the cylinder 4, as by brazing or welding.

The fork 27 of the operating handle is shown integrally formed with a forked head, generally designated by the numeral 29 and having a bore 31 therein for receiving one end of a tubular member 32, which constitutes the operating handle 23.

The forked head 29 has a complementary fork 33 provided with a counterbore 34 normally sealed by a suitable cap 35, received in threaded engagement with the wall of the counterbore 34, as shown in Figure 2.

The pivot pin or stud 25 is shown received in threaded engagement with the fitting 28 in axial alignment with the stud 24. The pivot stud 25 further has an enlarged head or flange 36 received in the counterbore 34 and providing a seat for a suitable packing cup 37, secured to the stud 25 by a suitable washer 38 and lock nut 39, the latter being received in threaded engagement with the reduced end portion 41 of the stud 25.

A fluid duct 42 is provided in the stud 25 and communicates with an inclined duct 43 provided in the fitting 28. The passage 43 extends through the wall of the cylinder 4 and cooperates with the duct 42 to establish communication between the annular space 12 in the cylinder wall and the counterbore 34 in the head 29.

An important object of the present invention resides in the construction of the operating handle 23 which embodies a fluid reservoir 44 and a fluid circulating pressure pump, generally design-

nated by the numeral 45. The tubular member 32 secured to the head 29 provides the reservoir 44, and the forked head 29 is shown provided with an offset portion 46 bored to provide a pump cylinder 47, which preferably is arranged in parallel relation to the axis of the handle 23 and is laterally spaced therefrom, as shown in Figure 1.

A piston 48 is mounted in the pump cylinder and has a head 49 shown provided with a suitable packing 51 secured in position thereon by a valve cage 52 having a spring-actuated check valve 53 mounted therein and normally closing a duct 54 provided in the piston head 49. One end of the duct 54 is in communication with a cross duct 55 in the pump piston 48, as shown in Figure 3, which connects the duct 54 with the pump cylinder 47. The pump cylinder is in constant communication with the fluid reservoir 44 through an enlarged passage 56, shown in Figure 1.

A fluid circulating passage 57 establishes communication between the adjacent end of the pump cylinder 47 and a valve chamber 58 having a spring-actuated check valve 59 therein which normally closes the fluid circulating passage 57 leading from the pump cylinder 47. A connecting passage 61 establishes communication between the valve chamber 58 and the counterbore 34, as shown in Figure 2. In this figure the check valve 59 and its complementary spring have been removed from the valve chamber 58 to more clearly disclose the fluid circulating passages, as will be understood.

Another important feature of the invention resides in the means provided for operating the pump when the operating handle 23 is oscillated with respect to the jack cylinder 4.

To thus operate the pump piston 48, a suitable yoke, generally designated by the numeral 62 and shown comprising spaced links 63, has one end pivotally connected to the projecting end portion of the pump piston 48 by a suitable pivot pin or bolt 64. The opposite ends of the links 63 of the yoke 62 are pivotally connected to the wall of the main cylinder 4 by suitable pivot elements 65, shown fixed to the wall of the cylinder 4, as indicated in Figure 4. The pivot elements 65 are located at an elevation above the pivotal connection between the operating handle 23 and the main cylinder 4, whereby when the handle is swung upwardly from the position shown in Figure 1, the pump piston 48 will be moved upwardly or outwardly in the cylinder 47, as will be understood by reference to Figure 3, thereby creating a vacuum in the lower portion 66 of the pump cylinder whereby a portion of the pressure fluid or liquid is drawn from the reservoir through check valve 53 into the cylinder portion 66, as indicated by the arrows in Figure 3. During such upward movement of the operating handle, the check valve 59 will seal the passage 57 between the pump cylinder and valve chamber 58. When the operating handle is thrust downwardly the pump piston is forced in a direction towards the main cylinder 4, whereby the fluid drawn into the end portion 66 of the pump cylinder will be forced upwardly past the check valve 59, through the valve chamber 58 and passage 61 into the counterbore 34, from whence it is forced through passages 42 and 43 into the annular space or chamber 12 provided between the ram 8 and cylinder wall 4. The fluid thus pumped into the annular chamber 12 will enter beneath the ram head 9 and thereby cause the ram to be thrust

upwardly against or into engagement with the load.

Means is also provided for releasing the pressure fluid from the main cylinder 4 to lower the jack. The means provided for thus releasing the pressure fluid in the main cylinder is shown comprising a needle valve 67 adapted to normally engage a seat 68 to prevent fluid flow through a duct 69 connecting the valve chamber 58 with the reservoir 44 provided within the handle 32. The needle valve 67 has a valve stem 71 which is threaded as indicated at 72, whereby the valve stem 71 may be secured to the forked head 29 in position to close the release port 69, as will be understood by reference to Figures 1 and 2. The opposite end of the valve stem 71 passes through a head 73 secured to the outer end of the tubular member 32 of the handle. A suitable packing 74 prevents leakage between the stem 71 and head 73. A packing gland 75 retains the packing in place in the head 73. A suitable hand grip 76 is secured to the end portion 77 of the valve stem 71 whereby the stem may readily be rotated to unseat the needle valve 67 from its seat 68.

When the operating handle is oscillated to pump fluid into the main cylinder to lift the load, the needle valve 67 is engaged with the seat 68 and when it is desired to release the pressure fluid from the main cylinder to permit it to return to the fluid reservoir 44, the valve stem 71 is slightly rotated by manipulation of the hand grip 76, whereby the annular chamber 12 in the main cylinder is in direct communication with the fluid reservoir 44 through the fluid circulating passage 43, 42, counterbore 34 and passage 61, valve chamber 58 and duct 69, as will be understood by reference to Figure 2.

The novel jack herein disclosed is extremely simple and inexpensive in construction. The pump operating yoke provides a very simple and inexpensive operating mechanism for operating the pump piston by oscillation of the jack handle 23. In Figure 1 I have shown the pump located at the lower side of the operating handle in which position the end portions 78 of the legs of the yoke 62 are pivotally connected to the main cylinder 4 at an elevation above the pivotal connection between the operating handle and the main cylinder. Obviously, the pump cylinder could be otherwise located without departing from the scope of the invention so long as its location is such that oscillation of the pump handle will impart reciprocal movement to the pump piston to pump the pressure fluid from the reservoir to the main cylinder.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. In an apparatus of the class described, a cylinder, a plunger or ram mounted therein and projecting from one end of the cylinder, an operating handle mounted for pivotal movement with respect to the cylinder, a fluid reservoir, a pump in the handle having fluid circulating connections with the cylinder and reservoir, said

pump having a piston, and means connecting the pump piston with a fixed portion of the jack whereby oscillation of the handle relative to the cylinder will actuate the piston to pump fluid from the reservoir into the cylinder to project the ram from the cylinder.

5. In an apparatus of the class described, a cylinder, a plunger or ram mounted in the cylinder, an operating handle pivoted to the wall 10 of the cylinder, a fluid reservoir, a fluid circulating pump in the handle provided with a piston, a fluid circulating passage between the pump and reservoir, a valve controlled passage between the pump and said cylinder, a member having one end connected to the pump piston and its opposite end to a fixed portion of the jack whereby the pump piston may be actuated by oscillation of the handle relative to the cylinder, thereby to pump fluid from the reservoir into the cylinder to project the ram from the cylinder, and means carried by the handle for releasing the pressure fluid from the cylinder.

2. In an apparatus of the class described, a cylinder, a plunger or ram mounted for reciprocal movement therein, an operating handle mounted for pivotal movement with respect to the cylinder and having a fluid reservoir therein, a pump cylinder secured to the operating handle and offset from the axis of the handle, a fluid 15 passage connecting the pump to the reservoir, a piston in the pump cylinder having one end projecting therefrom, a valve controlled fluid passage between the pump cylinder and the main cylinder, and means operatively connecting the 20 projecting end of the pump piston with a fixed portion of the jack whereby oscillation of the handle will actuate the piston to pump fluid from the reservoir into the main cylinder to project the ram therefrom.

3. In a hydraulic jack, a main cylinder mounted on a suitable base, a ram mounted for reciprocal movement therein, an operating handle mounted for pivotal movement with respect to the cylinder and having a fluid reservoir therein, a pump cylinder secured to the operating handle and offset from the axis of the handle, a fluid 25 passage connecting the pump to the reservoir, a piston in the pump cylinder having one end projecting therefrom, a valve controlled fluid passage between the pump cylinder and the main cylinder, and means operatively connecting the 30 projecting end of the pump piston with a fixed portion of the jack whereby oscillation of the handle will actuate the piston to pump fluid from the reservoir into the main cylinder to project the ram therefrom.

4. In a hydraulic jack, a main cylinder, a ram mounted for reciprocal movement in said cylinder and having one end projecting from the top of the cylinder, an operating handle mounted for pivotal movement with respect to the cylinder and having a fluid reservoir therein, a pump cylinder secured to the operating handle and offset from the axis thereof, a fluid passage connecting the pump cylinder to the reservoir, a piston in the pump cylinder having one end 35 projecting therefrom, a valve controlled passage between the pump cylinder and the main cylinder, and a pump operating link having one end pivotally connected to the pump piston and its opposite end to the main cylinder whereby 40 when the operating handle is oscillated relative to the main cylinder, the piston is operated to pump fluid from the reservoir to the main cylinder to project the ram therefrom.

5. In a hydraulic jack, a cylinder, a ram mounted for reciprocal movement in the cylinder, an operating handle mounted for pivotal movement with respect to the cylinder and having a fluid reservoir therein, a pump cylinder secured to the operating handle and offset from the axis thereof, a fluid passage connecting the pump cylinder to the reservoir, a piston in the pump cylinder having one end projecting therefrom, a valve controlled passage between the pump cylinder and the main cylinder, a pump operating yoke having one end pivotally connected to the pump piston and its opposite end to the main cylinder at an elevation above the pivotal mounting of the handle whereby when the operating handle is oscillated relative to the main cylinder, the piston is operated to pump fluid from the reser-

voir to the main cylinder to project the ram therefrom, a fluid release port in the handle, a valve for closing said port, and means at the end of the operating handle whereby the fluid release valve may be conveniently operated to control return flow of the fluid from the main cylinder to the reservoir.

6. In a hydraulic jack, a suitable base having an upright cylinder secured thereto, a ram in said cylinder, an operating handle pivotally mounted on said cylinder and having a reservoir therein, an inelastic pressure liquid in the reservoir, a pressure pump in the handle adjacent to the pivotal connection between the handle and said cylinder, said pump comprising a piston disposed in substantially parallel relation to the axis of the handle, a valve controlled passage connecting the pump with the interior of the cylinder through said pivotal connection, a pump operating yoke having one end pivotally connected to the pump piston and its opposite end to the jack cylinder, whereby when the handle is oscillated with respect to the cylinder, the piston is operated to pump liquid from the reservoir into said cylinder to project the ram therefrom, a liquid release valve within said handle, and a rotatable control element at the outer end of the handle whereby the liquid release valve may be conveniently operated to control the return flow of the liquid to the reservoir to lower the jack.

7. In a hydraulic jack, a base, an upright cylinder having one end secured thereto in leak-

tight relation, a ram in said cylinder, an operating handle mounted for pivotal movement with respect to the cylinder, said handle comprising an elongated tubular member providing a reservoir, an inelastic pressure liquid in said reservoir, a pressure pump in the lower portion of the handle including a piston laterally offset from the axis of said handle, a valve-controlled passage connecting the pump with the interior of the cylinder through the pivotal connection between the handle and said cylinder, a member having one end connected to the pump piston and its opposite end to the jack cylinder whereby oscillation of the handle will operate the pump, a release valve for releasing the pressure liquid from the cylinder to lower the jack, and an operating member for said release valve, said reservoir, pump, release valve and valve operating member being embodied in the construction of the handle, whereby all of said parts may be assembled as a unitary structure independently of the jack cylinder and base.
